HEAT TRANSFER MEANS AND METHOD OF ASSEMBLY

Hampton J. Dailey, Bloomfield, N. J., assignor to Westinghouse Electric Corporation, East Pittsburgh, Pa., a corporation of Pennsylvania

Application July 18, 1942, Serial No. 451,448

4 Claims. (Cl. 189—36)

1

This invention relates to heat transfer means and particularly to cooling means applied to and in combination with an external electrode of an electron discharge device, and method of assembly therewith.

Heretofore electron discharge devices have been constructed with envelopes partly of glass and partly of metal, at least one of the external metal parts constituting an electrode. A particular instance of such construction is incorporated in the present showing wherein the external metal part constitutes in part an anode. Consequential upon the heat developed in the metallic anode, the junction between the metal and glass is subjected to high temperature differences. Radiators of one sort or another have been applied to the external part of the metallic electrode, and in application of a sleeve type of radiator the fabrication has involved use of solder for obtaining tight contact for insuring maximum conduction of heat from the electrode to the radiator. The solder, on entry of the electrode into the core, is frequently forced from the intervening device and strikes the glass part of the envelope either causing immediate breakage or a weakened spot which develops into a defect and point of leakage. To avoid this, insufficient solder has frequently been employed thereby leaving an air gap between the electrode and radiator core with resultant loss of conduction.

An object of the present invention is to overcome the detrimental effects of prior art construction and method of fabrication.

A further object of the invention is to improve the structure and method of fabrication and at the same time reduce discards or shrinkage in manufacture and development of defective devices in use from the cause mentioned.

Another object of the invention is to obtain maximum heat conduction from the electrode to the radiator core.

Yet another object is to reduce the time and attention required of the operator in making a perfect assembly of the electrode and radiator core.

Still further objects and advantages will become apparent both by direct recitation thereof and by implication from the context as the description proceeds.

Referring to the accompanying drawing in which like numerals of reference indicate similar parts throughout the several views;

Figure 1 is a longitudinal sectional view of an electron discharge device with a cooling means applied thereto in accordance with my invention;

2

Figure 2 is a sectional view of the core showing steps of fabrication; and

Figure 3 is a sectional view of anode and core of Fig. 1 about to be assembled.

In the specific embodiment of the invention illustrated in said drawing, the reference numeral 10 designates an electron discharge device in general, having usual triode or other electrodes of which the anode 11 shown herein is formed as part of the envelope and provides a peripheral rim portion 12 sealed into an edge margin of glass portion 13 of said envelope. The anode structure, while not per se novel, enters into the present invention as illustrative of the metallic portion of the electron device to which an external radiator is to be applied. Said anode is shown as an inverted dome the base part of which curls or flares outwardly at 14 and then downwardly to form said rim portion 12 spaced from and engirdling a part of the body of the anode nearest the base part thereof. The structure accordingly provides an inverted channel 15 between the dome or body portion of the anode and said rim portion 12. The glass portion 13 of the envelope is provided with a reentrant edge margin 16, and it is this reentrant margin which is sealed to the said rim portion 12 of the anode.

The heat transfer means or radiator, designated in general by numeral 17, comprises a metallic core 18 the lower portion whereof has fins 19 extending longitudinally thereof and radiating therefrom. The outer longitudinal edges of the fins are here shown engaging and attached to the inner face of a ring 20 surrounding the annular series of fins. As here shown, the fins are situated at their inner longitudinal margins in grooves 21 provided in the outer surface of the lower cylindrical part of the core. Other constructions of fins and means of attachment may be substituted.

The upper part of core 18 is hollowed, thereby providing an anode cavity 22 shaped to conform to the dome shape of the anode. Assembly clearance and manufacturing tolerance results in a minute space existing between the cavity wall and the anode, and that space is filled with a film of solder 23 during fabrication. It may now be pointed out that the upper part 24 of core 18 is annular, due to the cavity 22 therein, and this annular part of the core enters between the reentrant glass margin 16 and the body of the anode as well as between the channel-forming parts of the anode, so that the upper end of the core is above the edge of the glass and therefore solder ejected from the provided space is apt to,

and frequently has in the past, contacted with and often lodged upon the glass. The present invention overcomes this prevalent detrimental condition.

In the upper end edge of the annular part 24 of the core is provided an overflow catch basin formed by means of an annular channel 25. As this channel is interposed between the space for the solder and the glass part of the envelope, excess solder from said space will lodge in said channel, thereby protecting the glass. Since the channel is annular or continuous around the anode, large amounts of solder extruded at one position will flow around to parts of the channel where no solder has been caught, and thus the channel will accommodate irregularity of extrusion of the solder. If desired, and where space permits, the outer wall of the catch basin or channel may be made higher than the inner wall, as shown, to more positively prevent overflow of the extruded solder.

In manufacture, and as indicated by the showing of Figure 2, the cavity 22 of the core is appropriately cleaned and kept in best condition for adherence of the solder. Cleaning may be by acid or otherwise, after which a flow of hydrogen is maintained in the cavity until ready to insert the anode therein. Solder 26 in proper amount is placed in the cavity and the core is heated so that all parts thereof are above the melting point of the solder. Flame 27 is indicative of appropriate heating means.

Next, the anode is forced, as being done in Fig. 2, gradually and firmly into said cavity, the anode displacing the melted solder and forcing it to rise in the space between the anode and core. The fact that the entire core is above the temperature of the solder assures flow, without solidification, to the upper edge of the core. Likewise, excess solder extruded from the space, will continue in its liquid state and will flow into the catch basin or channel 25 and will level-off therein to take care of a very considerable overflow. Thus it can be assured that the solder completely fills the space between the anode and core and that the extruded excess will be accommodated and retained by the channel so none will contact the glass part of the envelope. Cooling of the core is then permitted and the solder will accordingly harden in place giving full surface connection throughout the cavity with the anode.

Since the various details of construction, and steps involved in the method, as well as the precise relation and functioning of parts are subject to variation and change without departing from the inventive concept or scope of the invention, it is intended that all matter contained in the

specification or illustrated in the drawing, shall be interpreted as exemplary and not in a limiting sense. It is also to be understood that the following claims are intended to cover all of the generic and specific features of the invention herein shown and described and all statements of the scope of the invention herein set forth as a matter of language which might be said to fall therebetween.

10 I claim:

15 1. A heat exchange means comprising a core from said device through the material of the core, said cavity adapted to contain material in a fluid state subject to extrusion at the upper edge of the cavity upon introduction of said device into the cavity, said core having means for accommodating excess of the fluid material extruded from the cavity.

20 2. A heat exchange means comprising a core from said device through the material of the core, said cavity adapted to contain material in a fluid state subject to extrusion at the upper edge of the cavity upon introduction of said device into the cavity, said core having a channel for accommodating excess of the fluid material extruded from the cavity.

25 3. A heat exchange means comprising a core from said device through the material of the core, said cavity adapted to contain material in a fluid state subject to extrusion at the upper edge of the cavity upon introduction of said device into the cavity, said core having a continuous annular channel for accommodating excess of the fluid material extruded from the cavity.

30 4. A heat exchange means comprising a core from said device through the material of the core, said cavity adapted to contain material in a fluid state subject to extrusion at the upper edge of the cavity upon introduction of said device into the cavity, said core having a channel for accommodating excess of the fluid material extruded from the cavity.
